UNITED STATES PATENT OFFICE.

CYRUS W. COURTNEY AND JESSIE G. COURTNEY, OF DONIPHAN, IDAHO.

DESIGN FOR AN INKSTAND.

SPECIFICATION forming part of Design No. 26,923, dated April 20, 1897.

Application filed February 1, 1897. Serial No. 621,571. Term of patent 14 years.

To all whom it may concern:

Be it known that we, CYRUS W. COURTNEY and JESSIE G. COURTNEY, citizens of the United States, residing in Doniphan, in the 5 county of Logan and State of Idaho, have invented and produced a new and original Design for an Inkstand, of which the following is a specification, reference being had to the accompanying drawing, showing a part thereof.

10 The said drawing is a representation of the bust, neck, and head of a human being, with the head, however, illustrated as extended and with a practically flat face portion rounded toward the sides. The eyes and the nose 15 are represented near the upper end of this head portion, while the mouth is represented as opened and occupies a greater portion of the space occupied by the face. The representation of the mouth is of course in an abnormal and ludicrous position, but it is purposely made in this manner to attract attention, since the design is to be used for advertising purposes, and therefore when the advertising matter is placed within the space 20 bounded by the lines of the mouth it is manifestly the most prominent feature of the device. From the sides of the lower portion of

this figure, or from the shoulder portion of the bust, are the forwardly-extending arms, represented at the ends with extended fingers. 30 These extended fingers on opposite sides of the figure are practically opposite each other. At the upper end of the bust portion of the figure and on the sides of the neck are represented openings or depressions extending 35 downwardly into the body portion of the figure.

The above design is novel, ornamental, and is a symmetrical and pleasing design for an 40 inkstand.

Having thus described our invention, what we claim as new, and desire to secure by Letters Patent, is—

The design for an inkstand, substantially as shown and described.

In testimony whereof we have signed this specification in the presence of two subscribing witnesses.

CYRUS W. COURTNEY.
JESSIE G. COURTNEY.
